UNITED STATES PATENT OFFICE.

WILLIAM MENNE, OF UNION CITY, NEW JERSEY.

PRESERVER JAR.

Application filed August 11, 1926. Serial No. 128,532.

The main object of this invention is to provide a preserving jar equipped with a novel method of retaining the cap on the jar in sealed position in such manner that it 5 may be easily removed when opening without resorting to the use of tools such as a knife, which latter is commonly used to pry the cover from place.

Another object is to provide a novel type 10 of valve on the cover of the preserving jar, which when manipulated, opens a channel entering into the jar and exhausts whatever vacuum contained. In the so-called cold-pack method of preserving, the jars filled 15 with contents are immersed in water or other liquid medium in a container. The level of this water just about covers the tops of the jars during the cooking operation. After the jars and their contents have been 20 subjected to cooking a sufficient length of time, the covers or caps are replaced and the securing means are tightened down. In this way, no air is permitted in the jars but when cooling, the contents of the jars form 25 a partial vacuum which makes it difficult to remove these caps and in their removal, injury to the fingers often occurs. To eliminate this, I have provided a novel type of valve which opens a channel as stated and 30 releases or exhausts this vacuum.

The above and other objects will become apparent in the description below, in which characters of reference refer to like-named parts in the drawing.

Referring briefly to the drawing, Figure 35 1 is a longitudinal sectional elevational view of the preserve jar, showing the same with the cap mounted in place and the valve in locked position.

Figure 2 is a top plan view of Figure 1.

Figure 3 is an enlarged fragmentary elevational view, showing the means of holding the cap securely and releasably in place on the jar.

Figure 4 is a longitudinal sectional elevational view of the valve mechanism.

Figure 5 is a bottom plan view of Figure 4.

Referring in detail to the drawing, the 50 numeral 10 indicates a cylindrical transparent glass jar in common use for the storing of preserves. The jar is provided with a bottom integral with the walls of the member and at the top has a somewhat reduced neck 12. This neck is covered by a 55 cap 13 which is substantially elliptical in

shape, having its major axis of a dimension substantially equal to the diameter of the large part of the jar and its minor axis somewhat greater than the diameter of the neck of the jar. Diametrically opposite each other, lugs 13^a and 14 extend outwardly from the neck of the jar and their bottom surfaces are provided with depressions 15. At the major axis of the cap on both sides, 65 inturned ledges 16 are provided which serve as platforms for resilient fingers 17 which have one of their ends riveted to said platforms. At the center of the cap, a converging wall 18, circular in outline, is formed on 70 the bottom face of the cap. Within the open chamber formed by this wall, the head 19 of a valve is rotatably mounted. Said valve has a shank 20 which protrudes upwardly thru an opening in the cap 13 and a wing nut 21 surmounts said shank. The wing nut is rotatably mounted on a flange 22 fixed to the surface of the cap 13. A channel 23 passes vertically thru the wing nut 21 and shank 20 and ends in the head 19 of the valve. A horizontal channel 24 extends horizontally and diametrically across the valve head 19 and communicates with the channel 23. The horizontal channel 24 is adapted to align with a pair of diametrically opposite vents 25 which are formed and pass thru the wall of the cup-shaped portion 18.

The preserve jar when in use is filled with any desirable contents and the cap is fitted in place. Said cap is fitted by rotating the 90 latter from a position in which the ledges 16 are at right angles to the lugs to a position where they align therewith. As the ledges align with the lugs 13^a and 14, the resilient fingers 17 ride into the depressions 95 15 formed on the underside of these lugs and releasably retain the cap in place and yieldably urge the upper portion of the cap down upon the generally used rubber washer 26, thus sealing the chamber of the 100 preserve jar. To permit air to enter the jar, the wing nut 21 is turned until a hissing sound is heard, indicating that the horizontal channel 24 has been aligned with the vents 25, thus allowing the jar to be opened 105 easily and without binding.

I claim:—

1. A preserve jar comprising a jar proper, a pair of diametrically opposed lugs on said jar, a cap elliptical in shape, ledges on said 110 jar positioned on the major axis thereof, cap positioned on the major axis thereof, resilient fingers mounted on said ledges,

and means on said lugs engaging said fingers for keeping said cap releasably in place on the jar.

2. A preserve jar comprising a jar proper, a pair of diametrically opposed lugs on said jar, a cap elliptical in shape, ledges on said cap positioned on the major axis thereof, resilient fingers coiled spirally mounted on said ledges, means on said lugs engaging the coiled portions of said fingers for securing said cap in place releasably on the jar, and a valve mounted on said cap.
3. A preserve jar comprising a jar proper, a pair of diametrically opposed lugs on said jar, a cap elliptical in shape, ledges on said cap positioned on the major axis thereof, resilient fingers coiled spirally mounted on said ledges, means on said lugs engaging the coiled portions of said fingers for securing said cap in place releasably on the jar,

said lugs having depressions on their underside, the coiled portion of said fingers entering into said lugs to lock the cap in place on the jar in closed position, a valve mounted on said cap for permitting air to enter into the sealed chamber, and means for closing said valve.

4. A preserve jar comprising a jar proper, a pair of lugs on opposite sides of said jar, a cap elliptical in shape, ledges on said cap positioned on the major axis thereof, resilient fingers mounted on said ledges, means on said lugs engaging said fingers for securing said cap in place releasably on the jar, said means comprising depressions on the undersides of the lugs, said fingers entering into said depressions to lock the cap in closed position.

In testimony whereof I affix my signature.
WILLIAM MENNE.
